UNITED STATES PATENT OFFICE.

JAMES N. McCANN AND WILLIAM SCROGGIN, OF BEARDEN, ARKANSAS.

COLTER-CLAMP.

SPECIFICATION forming part of Letters Patent No. 550,878, dated November 26, 1895.

Application filed August 26, 1895. Serial No. 560,587. (No model.)

To all whom it may concern:

Be it known that we, JAMES N. McCANN and WILLIAM SCROGGIN, citizens of the United States, residing at Bearden, in the county of 5 Ouachita and State of Arkansas, have invented a new and useful Colter-Clamp, of which the following is a specification.

Our invention relates to a clamp for securing colters to plow-beams; and the object in 10 view is to provide a simple, inexpensive, and efficient device adapted to be applied with facility to a plow-beam to form the means of attachment of a colter-shank, and, furthermore, to provide simple means for adjusting 15 the colter vertically with relation to the plow-beam and securing the same at the desired adjustment.

Further objects and advantages of the invention will appear in the following description, 20 and the novel features thereof will be particularly pointed out in the appended claim.

In the drawings, Figure 1 is a side view of 25 a colter-clamp constructed in accordance with our invention applied in the operative position to a plow. Fig. 2 is a longitudinal section of the clamp. Fig. 3 is a detail view in perspective of the clamp detached. Fig. 4 is a transverse section of the upper clamp-plate 30 in the plane of the key.

Similar numerals of reference indicate corresponding parts in all the figures of the drawings.

1 designates a plow-beam to which our improved colter-clamp is applied, the clamp comprising a lower plate or member 2, which is bolted to the under side of the plow-beam, and an upper plate or member 3, which is bolted to the upper side of the beam, common 35 bolts 4 being employed to secure both plates or members to the beam.

The upper and lower plates or members of the clamp are provided, respectively, with aligned openings 5 for the reception of a colter-shank 6, a corresponding opening 7 being formed in the plow-beam, through which the shank extends, and the upper plate or member is provided with a transverse perforation 8 for the reception of a key 9, said perforation being formed at the rear end of the ver-

tical opening in the plate or member and having one-half of its diameter overlapping the opening, whereby the key when fitted in the perforation projects at one side into the opening to engage one of a series of rounded notches 10, formed in the rear edge of the colter-shank. One end of this key is threaded to engage a threaded portion of the perforation, whereby displacement of the key by jar- 55 ring is prevented.

The object in employing a key fitted in a transverse perforation, which breaks into and thereby communicates with but does not extend through the opening in which the colter-shank is arranged, is to avoid the necessity of 60 perforating the colter-shank and provide for the proper adjustment of the parts by forming notches in the rear edge of the shank. Such notches may be formed, as indicated in the drawings, to secure the proper locking of the 65 colter in the desired position without materially weakening the shank, and in addition to this it will be seen that by employing notches instead of transverse openings or perforations in the shank the key does not bear 70 or resist any of the strain exerted upon the colter. The pressure of the upper end of the colter is from the key, and hence while displacement is prevented the key is not strained 75 and is not liable to be broken in use.

Various changes in the form, proportion, and the minor details of construction may be resorted to without departing from the spirit or sacrificing any of the advantages of this 80 invention.

Having described our invention, what we claim is—

A colter clamp comprising upper and lower plates or members secured, respectively, to the upper and lower sides of a plow beam by 85 means of common bolts and provided with aligned openings, the upper plate or member being provided with a transverse perforation which is arranged contiguous to and breaks 90 into the rear end of the opening in said plate or member, and a key fitted in said transverse perforation with one side projecting 95 into the opening in the plate or member, said key being threaded to engage a threaded portion of the perforation, in combination with 100

a colter shank adapted to fit in said aligned openings and provided in its rear edge with a series of notches to engage the transverse key whereby the shank is held at the desired adjustment by the key without straining or subjecting the same to transverse pressure in use, substantially as specified.

In testimony that we claim the foregoing as

our own we have hereto affixed our signatures in the presence of two witnesses.

JAMES N. McCANN.
WILLIAM SCROGGIN.
